Primary Examiner — Selina Sikder(74) *Attorney, Agent, or Firm* — Crestron Electronics Inc.(57) **CLAIM**

The ornamental design for a wall mounted button panel with split buttons, as shown and described.

DESCRIPTION

FIG. 1 shows a front elevational view of a wall mounted button panel with split buttons.

FIG. 2 shows an isometric projection of the wall mounted button panel with split buttons.

FIG. 3 shows a left side elevational view of the wall mounted button panel with split buttons.

FIG. 4 shows a right side elevational view of the wall mounted button panel with split buttons.

FIG. 5 shows a top plan view of the wall mounted button panel with split buttons; and,

FIG. 6 shows a bottom plan view of the wall mounted button panel with split buttons.

The broken line portion of the figure drawings is included to show unclaimed subject matter only and forms no part of the claimed design.

1 Claim, 4 Drawing Sheets(56)
